UNITED STATES PATENT OFFICE.

MAHLON E. LAYNE, OF HOUSTON, TEXAS.

WELL-SCREEN-FORMING DEVICE.

Application filed April 19, 1923. Serial No. 633,085.

To all whom it may concern:

Be it known that I, MAHLON E. LAYNE, a citizen of the United States, residing at Houston, in the county of Harris and State 5 of Texas, have invented a new and useful Well-Screen-Forming Device, of which the following is a specification.

This invention relates to a device for forming well screens, and is particularly 10 directed to a device which may be operated from the well surface to open screen apertures in well pipe after same has been positioned in a well.

It is an object of the invention to provide 15 a device adapted to be lowered into a well casing and manipulated from the well surface and vertically translated to form vertical rows of relatively spaced screen apertures with the rows circularly spaced at 20 predetermined intervals.

Another object is to provide a device capable of simultaneously forming a plurality of screen apertures.

Another object is to provide a device 25 which is particularly adaptable for use in connection with double wall well-screens in which the inner wall is provided with vertical rows of holes with which the device cooperates, and an outer wall normally closing said holes and in some instances scored or split in the region of each hole to facilitate a perforating operation.

Various other objects and advantages will 35 be more fully apparent from the following description of the accompanying drawings which form a part of this disclosure, and which illustrate a preferred form of embodiment of the invention.

Of the drawings:

Figure 1 is a vertical section of a well 40 screen with my screen forming device being lowered therein.

Fig. 2 is a similar view with the device in section and its parts in position of operation.

Fig. 3 is an elevation of the device looking at the left hand side of Fig. 1.

Fig. 4 is a section on line 4—4 of Fig. 1.

Fig. 5 is a section on line 5—5 of Fig. 2.

Fig. 6 is a view similar to Fig. 2, of a modified form of device.

Fig. 7 is a section on line 7—7 of Fig. 6.

Fig. 8 is a view similar to Fig. 2, of another modification.

Fig. 9 is an elevation of the device shown

in Fig. 8, looking at the left-hand side of said figure.

Fig. 10 is a section on line 10—10 of Fig. 8.

Fig. 11 is a section on line 11—11 of Fig. 8.

Fig. 12 is a section on line 12—12 of Fig. 8.

Fig. 13 is a section on line 13—13 of Fig. 8.

The device herein referred to is especially adaptable for use in the formation of well screens which are manufactured with normally closed screen apertures to be subsequently opened after the screen is positioned in a well bore at the desired point of production, and is more particularly adapted for use in the formation of double wall well screens in which an inner apertured casing functions as a means of positively guiding the device in a perforating operation to open screen apertures in the outer wall or casing.

In making and installing well screens of this general character it has heretofore been proposed to open the screen apertures by hydraulic or explosive pressure, but such methods are objectionable, first for the reason that in producing a pressure

within the casing of a degree sufficient to open the screen apertures, and especially in the use of explosives there is great

danger of injury to the well casing, it having been found that in some cases the explosion was so sharp as to open or stretch

the connecting couplings to such an extent that when attempting to lift the casing the couplings would slip off the threads of the

casing sections, and second for the reason that the degree to which the screen apertures are opened cannot be accurately determined or controlled, for instance those

screen apertures which happen to be adjacent hard formations will not be opened, at least not to the same extent as those adjacent softer formations.

With the herein described device, the screen apertures are positively opened to a predetermined degree regardless of the nature of the formation contacting the various portions thereof. And further, with the present device it becomes possible to open the screen apertures to a limited extent in the first instance and to subsequently further open said apertures as conditions

may require, and with a certainty of accurately re-engaging the previously formed apertures. This is of great advantage in bringing in wells under high initial pressure, necessitating a screen with only limited openings or screen apertures, and where later the pressure subsides and a more liberal opening is desired. Further in wells in sand formations, the fineness or coarseness of the screen openings should vary according to the fineness or coarseness of the sand in such formations and should be under positive control of the operator, so that in a well bore through formations of different characters it is possible to open one portion of the screen more than another. It will be understood that that portion of the screen adjacent hard formations should be opened to a greater degree than that which is adjacent soft formations for the reason that large screen apertures adjacent soft formations will usually admit too much sand into the well, and further it will be evident that with the heretofore proposed methods of opening the screen apertures by hydraulic or explosive pressure the reverse will be true, that is, in hard formations there is a greater resistance to the opening of the screen apertures, resulting in smaller apertures where larger apertures are desired and in soft formations where such resistance is least the apertures will be relatively large where smaller apertures are desired.

With those types of mechanical perforators which are not positively guided in their perforating operation, an accurate spacing of the perforations is not possible, and in cases where it is desired to reperforate a casing to provide a more open screen or to clean previously made perforations, such unguided perforator cannot be depended upon to engage the previously made perforations and is exceedingly liable to form a new set of perforations so close to the first formed set as to seriously weaken the strength of the entire screen.

My improved device permits me to positively open the screen apertures in any portion of the screen to any degree desired, and after the screen has been set in the well bore, and to subsequently, accurately and positively re-engage said apertures to increase the degree of opening or to clean out such apertures as may have become clogged or cemented shut by the lime or other incrusting contents of the formations.

In the drawings I have illustrated a well-screen structure which consists of an inner casing or pipe 1 which is provided with a plurality of spirally arranged perforations 2 relatively positioned so as to form longitudinal rows relatively spaced around the pipe, and an outer casing or pipe which is formed of a metal ribbon 3 wound spirally around the inner pipe coil on coil to cor-

respond to the spiral progression of the perforations 2 and preferably with the lower half of the ribbon overlapping the perforations. The ribbon is grooved or scored lengthwise as at 4 and is split inwardly from its lower edge to the groove 4 on opposite sides of each of the perforations 2, as indicated at 5, to define tongues 6 overlying the perforations.

The ribbon 3 is preferably of substantial thickness so as to materially strengthen the inner pipe and also to provide tongues of sufficient thickness to withstand hard usage, and for this reason the groove 4 is particularly advantageous in contributing to an easy bending outwardly of the tongues.

A screen structure of this type is fully illustrated and described in my copending application entitled "Well screen and method of making same", Case A, Serial No. 633,082, filed Apr. 19, 1923, to which reference may be had if desired.

It will be stated that in so far as the present invention is concerned, the specific constriction of the screen is immaterial so long as it embodies the general characteristics of the type of screen shown, it being evident that other specific forms of screens are adaptable for use in connection with the herein disclosed device, one of such forms being shown and described in my copending application entitled "Well screen and method of making same" Case B, Serial No. 633,083, filed Apr. 19, 1923, and still another in the Patent No. 1,304,493 to Ollyn A. Layne.

The device herein illustrated has a body comprising a screw-threaded head 10 and two opposed relatively spaced plates 11 dependingly secured to said head and supporting the operating mechanism of the device. The head 10 is connected to the lower end of a string of casing or pipe 12 which extends to the well surface, and by which the device is manipulated in the well.

Positioned between the plates 11 I provide pairs of guide rollers 13 which are journaled upon studs 14, and which maintain the tool centrally positioned within the well casing. At the opposite ends of the body and between the plates 11 are rotary pilot or locating wheels 15, each having a plurality of locating studs 16 projecting from their peripheries, said studs being relatively spaced to correspond with the longitudinal spacing of the perforations 2 in the inner casing 1 with which they engage during a perforating operation of the device.

Each wheel 15 has a shaft 17 projecting through transverse slots 18 in the opposite plates 11 with its ends engaged by the free ends of spring members 19, the opposite end of each spring being secured to the adjacent plate 11 by a stud 20, and its me-

dial portion engaging an abutment pin 21. This construction provides spaced toothed rotary locating members which are yieldingly urged towards the casing wall and which are adapted to intermesh with the apertures or perforations 2 in the inner casing 1 to guide the device during its longitudinal perforating operation.

Between the pairs of rollers 13 I provide 10 pairs of opposed toggle members or perforating pawls 22 pivotally supported in superposed relation between the plates 11 upon studs 23, and which are yieldingly urged to a horizontal position by springs 15 24, each spring extending through an aperture in the respective stud 23 with its free ends projecting between spaced pins 25 on the adjacent pawl. (See Figs. 2 and 5.)

In the operation of a device of the above 20 described character in forming a well screen, the device is lowered into the well as shown in Fig. 1. During such initial lowering of the device the punch members or pawls 22 occupy the position shown in 25 said figure, the springs 24 yieldingly urging said pawls against the casing. Having been lowered to the region of the screen, the device is rotated or otherwise manipulated until the studs 16 of the locator wheels register with one of the vertical rows of holes 2 in the inner casing 1, this engagement of the studs 16 into said 30 holes being automatic by reason of the locator wheels being constantly urged outwardly by the springs 19.

With the locator studs 16 meshing into the holes 2, the device is then pulled upwards, the free ends of the several punch members or toggle pawls 22 simultaneously 40 engaging through the holes 2 in the inner casing 1 and forcing the tongues 6 of the outer casing outwardly as said pawls assume a horizontal position. (See Fig. 2.) In this manner the tongues are bent outwardly away from the holes 2 in the inner casing, completing the formation of as many 45 screen apertures as there are pawls in the device. (Seven with the device herein shown). To form a second group of screen apertures in the same row, the device may be lowered below the first group and then elevated in the manner above described, or the device may if desired be first elevated above the first group and then forced downward.

This operation is repeated until a full 50 row of screen apertures is completed after which the device will be elevated or lowered to an unperforated portion of the inner casing 60 and subsequently rotated slightly to disalign the pawls and locator wheels relative to the holes in the inner casing. The device can then be translated to the perforated portion of the inner casing and then rotated to bring the locating wheels into mesh with the

next row of holes after which the device is manipulated as previously explained, to form the next rows of screen apertures. With a device having opposed sets of pawls as shown in Figs. 1 to 5 operated in connection with a screen having four vertical rows of holes, (see Fig. 5) this completes the formation of the screen.

In Figs. 6 and 7 is shown a modified form of structure in which is provided a single series of punch members or pawls 26 which are connected by bars 27 to act in unison, said bars being connected to opposed springs 28 which tend to urge the pawls to a horizontal position.

In the operation of this form of device it will at once be understood that only one row of screen apertures can be engaged at a time and that with a screen having four vertical rows of holes it will be necessary 80 to separately engage each row.

In Figs. 8 to 13 there is shown another modified form of device having four groups of punch members or pawls 30, providing a device which in one operation is capable 90 of forming four rows of screen apertures. In this form of device the body has an upper portion formed of two plates 31 between which the locating wheel or roller 32 is positioned, and a lower body portion formed of four relatively spaced angle irons 33 secured to a four-wing member 34 which in turn is secured between the lower ends of the plates 31, the lower ends of the angle irons 33 being maintained in spaced relation by spacing members 35 and bolts 36.

Rotatably mounted between the lower ends of the angle irons are four guide rollers 37 which engage the well casing and maintain the device centrally positioned 105 therein. The pawls 30 are pivoted on studs 38 and are connected by bars 39, opposed springs 40 being connected to the opposite ends of the bars and to the body and tending to yieldingly urge the pawls to a horizontal position. It is thus seen that the studs 38 mounting the pawls 30 are held rigidly in a definite spaced relation and thereby the diametrically opposed pawls 30 are in effect toggle members.

While well adapted to fulfill the objects primarily set forth it is to be understood that the invention is not to be limited to the specific embodiments herein disclosed, for it is susceptible of embodiment in various other forms, all coming within the scope of the following claims.

I claim:

1. A well-screen forming device including a body adapted to be longitudinally translated in a double-wall well casing having longitudinal rows of holes in its inner wall, diametrically disposed toggle members carried by the body and adapted to extend beyond the wall of the inner casing 120

when in horizontal position, said members cooperating with the walls of said holes during a longitudinal translation of the device to form screen apertures in the outer casing wall.

5. A well-screen forming device including a body adapted to be longitudinally translated in a double-wall well casing having longitudinal rows of holes in its inner wall, a plurality of diametrically disposed superposed toggle members pivoted in the body and adapted to extend beyond the inner wall when in horizontal position, said members cooperating with the walls of said holes during a longitudinal translation of the device to simultaneously form a plurality of screen apertures in the outer casing wall.

6. A well-screen forming device including a body adapted to be longitudinally translated in a double-wall well casing having longitudinal rows of holes in its inner wall, a plurality of diametrically disposed superposed pawls pivoted in the body to swing vertically above and below a horizontal position and adapted when in horizontal position to extend beyond the inner casing wall, said pawls cooperating with the walls of said holes during a longitudinal translation of the device to simultaneously form a plurality of screen apertures in the outer casing wall.

7. A well-screen forming device including a body adapted to be longitudinally translated in a double-wall well casing having longitudinal rows of holes in its inner wall, diametrically disposed toggle members carried by the body and adapted to extend beyond the wall of the inner casing when in horizontal position, said members cooperating with the walls of said holes during a longitudinal translation of the device to form screen apertures in the outer casing wall, and means yieldingly urging the toggle members to horizontal position.

8. A well-screen forming device including a body adapted to be longitudinally translated in a double-wall well casing having longitudinal rows of holes in its inner wall, a plurality of diametrically disposed superposed toggle members pivoted in the body and adapted to extend beyond the inner wall when in horizontal position, said members cooperating with the walls of said holes during a longitudinal translation of the device to simultaneously form a plurality of screen apertures in the outer casing wall, and means yieldingly urging the toggle members to horizontal position.

9. A well-screen forming device including a body adapted to be longitudinally translated in a double-wall well casing having longitudinal rows of holes in its inner wall, a plurality of diametrically disposed superposed pawls pivoted in the body to swing vertically above and below a horizontal position and adapted when in horizontal position to extend beyond the inner casing wall, said pawls cooperating with the walls of said holes during a longitudinal translation of the device to simultaneously form a plurality of screen apertures in the outer casing wall, and means yieldingly urging the pawls to horizontal position.

10. A well-screen forming device including a body adapted to be longitudinally translated in a double-wall well casing having longitudinal rows of holes in its inner wall, guide rollers carried by the body and maintaining the device centrally positioned within the well casing, an independent toothed locator wheel diametrically disposed in the body to rotate in a vertical plane

10. A well-screen forming device including a body adapted to be longitudinally translated in a double-wall well casing having longitudinal rows of holes in its inner wall, a plurality of diametrically disposed superposed pawls pivoted in the body to swing vertically above and below a horizontal position and adapted when in horizontal position to extend beyond the inner casing wall, said pawls cooperating with the walls of said holes during a longitudinal translation of the device to simultaneously form a plurality of screen apertures in the outer casing wall, and means yieldingly urging the pawls to horizontal position.

11. A well-screen forming device including a body adapted to be longitudinally translated in a double-wall well casing having longitudinal rows of holes in its inner wall, a plurality of diametrically disposed superposed pawls pivoted in the body to swing vertically above and below a horizontal position and adapted when in horizontal position to extend beyond the inner casing wall, said pawls cooperating with the walls of said holes during a longitudinal translation of the device to simultaneously form a plurality of screen apertures in the outer casing wall, and means compelling the pawls to operate in unison.

12. A well-screen forming device including a body adapted to be longitudinally translated in a double-wall well casing having longitudinal rows of holes in its inner wall, a plurality of diametrically disposed superposed pawls pivoted in the body to swing vertically above and below a horizontal position and adapted when in horizontal position to extend beyond the inner casing wall, said pawls cooperating with the walls of said holes during a longitudinal translation of the device to simultaneously form a plurality of screen apertures in the outer casing wall, a bar pivotally connected to the several superposed pawls, and spring means connected to the bar and urging the pawls to horizontal position.

13. A well-screen forming device including a body adapted to be longitudinally translated in a double-wall well casing having longitudinal rows of holes in its inner wall, an independent toothed locator wheel diametrically disposed in the body to rotate in a vertical plane with its teeth spaced to engage the holes in the inner casing, diametrically disposed toggle members carried by the body in vertical alignment with said wheel and adapted to extend beyond the wall of the inner casing when in horizontal position, said members cooperating with the walls of said holes during a longitudinal translation of the device to form screen apertures in the outer casing wall.

14. A well-screen forming device including a body adapted to be longitudinally translated in a double-wall well casing having longitudinal rows of holes in its inner wall, guide rollers carried by the body and maintaining the device centrally positioned within the well casing, an independent toothed locator wheel diametrically disposed in the body to rotate in a vertical plane

with its teeth spaced to have a rack and pinion engagement with said holes, diametrically positioned pawls pivoted in the body in superposed relation to swing vertically past a horizontal position, said pawls being vertically aligned with said toothed wheel and adapted to project beyond the inner casing wall when in horizontal posi-

tion, said pawls cooperating with the walls of said holes in the inner casing and be forced therethrough during a longitudinal translation of the device to form screen apertures in the outer casing wall. 10

Signed at South Pasadena, Cal. this 12th day of April 1923.

MAHLON E. LAYNE.
